WALL PAPER.

No. 17,476.

Patented July 19, 1887.

UNITED STATES PATENT OFFICE.

CHARLES H. PROVOST, OF BROOKLYN, NEW YORK.

DESIGN FOR WALL-PAPER.

SPECIFICATION forming part of Design No. 17,476, dated July 19, 1887.

Application filed June 1, 1887. Serial No. 240,010. Term of patent 7 years.

To all whom it may concern:

Be it known that I, CHARLES H. PROVOST, of Brooklyn, in the county of Kings and State of New York, have invented and produced a new and original Design for Wall-Paper, of which the following is a full, clear, and exact description.

My new design is fully illustrated in the accompanying print, to which reference is made. 10 a a represent circular solid spots of considerable size upon a background, b. The spots a a are disposed some distance apart. c c represent other circular solid spots of smaller size than the spots a a, and the spots c c appear scattered among the larger spots, a a, as shown clearly in the accompanying print. Upon the spots a c and ground b appear at stated distances the oval protuberances i i, as shown in the accompanying print.

I claim—

The design for wall-paper, substantially as herein shown and described.

CHARLES H. PROVOST.
